United States Patent

Des. 241,391
Patented Sept. 14, 1976

241,391

WALL MOUNTED RACK

George Weisenfeld and David Halpern, Studio City, Calif.,
assignors to International Tropic-Cal, Inc., Los Angeles, Calif.

Filed Mar. 20, 1975, Ser. No. 560,397

Term of patent 14 years

Int. Cl. D6—04

U.S. Cl. D6—114

Fig. 5

Fig. 1

Fig. 2

Fig. 3

Fig. 4

Fig. 6

FIG. 1 is a perspective view of the wall mounted rack showing our new design;

FIG. 2 is a right side elevational view, the left side view being identical thereto;

FIG. 3 is a front elevational view;

FIG. 4 is a rear elevational view;

FIG. 5 is a top plan view; and

FIG. 6 is a bottom plan view.

We claim:

The ornamental design for a wall mounted rack, substantially as shown.
